SANITARY COMB

Roger W. Davis, Natick, Mass.

Application October 9, 1937, Serial No. 168,123

4 Claims. (Cl. 132—11)

My present invention relates to combs, and more particularly to improved sanitary combs.

It is a well known fact that combs can and often do carry germs from one person to the other unless great care is taken to provide against this by sterilization. The only way to positively provide against contagion is to use a new comb each time and with the cost of the conventional comb being relatively high this procedure is impractical.

10 In my present invention, I have designed a very inexpensive comb which is practical and strong, and at the same time, can be manufactured in quantities for a small fraction of a cent a piece. These combs may be used once and thrown away.

15 They may be dispensed in transparent envelopes insuring the purchaser that he or she is receiving a sanitary article which has not been handled by others since delivery from the factory.

19 I am aware that attempts have been made to attain the end sought, by combs made from paper. The difficulty herein lies in the fact that strength is lacking. While the teeth of a comb should provide a certain resiliency yet the back of the comb must be as rigid as possible in both a horizontal direction and in a vertical direction. In my present invention I have attained the desired results by using a very hard fibre and forming the back of the comb in a special manner, all of which may be accomplished in one die operation.

20 The principal object of my invention is an improved, so called, sanitary comb;

25 Another object is an improved comb stamped from sheet fibre stock having a reinforced back portion adapted to stiffen the comb horizontally and vertically;

Still another object is an improved comb made from flat stock, as fibre, which presents a thickened back portion to the hand of the operator, and

30 Other objects and novel features comprising the construction and operation of my invention will be apparent as the description of the same progresses.

35 In the drawing illustrating the preferred embodiment of my invention;

Fig. 1 is a side elevation;

Fig. 2 is a fragmentary top plan, the scale being exaggerated;

Fig. 3 is an enlarged cross-section taken on the line 3—3 of Fig. 1;

Fig. 4 is another cross-section taken on the line 4—4 of Fig. 1, the lower portion being broken away;

Fig. 5 is another cross-section taken on the line

5—5 of Fig. 1, the lower portion being broken away.

Referring more in detail to the drawing, 10 indicates a comb, in general, being formed from sheet fibre of a uniform thickness. The comb is cut out by means of dies, preferably in one operation. The teeth 11 which are in the lower portion of the comb are of uniform thickness and preferably are resilient to a certain degree, as in a conventional comb. The back of the comb 15 incorporates three desirable features, as will hereinafter be explained.

It will be noted that the back portion of the comb indicated at 12 is provided with a plurality of angularly disposed ribs 13 and 14. These ribs are placed at an angle to the major axis of the comb and are alternated, the ribs 13 being on one side of the comb and ribs 14 being on the other side and in alternate relationship to each other. At the same time I have provided a central connecting web 15 between the ribs which is the original flat stock from which the comb is formed.

These ribs 13 and 14 are formed from the dies 20 preferably in the same operation which blanks and forms the teeth, sometimes referred to, as a 25 compound die operation.

As I have already stated the ribs 13 and 14 have several functions. Due to the fact that the ribs are pitched at an angle the back portion of the comb is braced against bending, either in a horizontal or vertical direction and at the same time I make use of the ribs as a holding surface of several times the thickness of the flat stock from which the comb is made thereby making it easier to handle. The teeth 11 have the same resiliency 30 as a comb made from moulded material. The fibre is preferably of the very hard pressed type and is not affected by water due to the relatively short life of the comb.

It will thus be seen that I have designed a very 40 cheap inexpensive comb which combines the essential characteristics of strength, either horizontally or vertically, with lightness all in one operation of manufacture.

It is to be understood that I may vary the size 45 and proportions of my invention within wide variations without departing from the spirit of the invention.

Having thus described my invention, what I claim as new is:

1. An improved sanitary comb comprising a tooth and back portion formed from flat stock of a uniform thickness, the said back portion being provided with a plurality of diagonally disposed embossed ribs.

2. An improved sanitary comb comprising a tooth and back portion formed from flat stock of a uniform thickness, the said back portion being provided with a plurality of diagonally disposed embossed ribs on each side of said back portion.
3. An improved sanitary comb having a tooth and back portion formed from sheet material having a uniform thickness, the said back portion being provided with a plurality of embossed ribs alternately disposed on each side of said back portion, a central web portion separating and surrounding said embossed ribs.
4. An improved sanitary comb having a tooth and back portion formed from sheet material having a uniform thickness, the said back portion being provided with a plurality of embossed ribs alternately disposed on each side of said back portion, a central web portion surrounding and connecting said ribs and being in the same vertical plane as said teeth. 5

ROGER W. DAVIS. 10
